UNITED STATES PATENT OFFICE.

HANS HOLZWARTH, OF HAMILTON, OHIO, ASSIGNOR OF ONE-HALF TO
ERHARD JUNGHAUS, SR., OF SCHRAMBERG, GERMANY.

GAS-TURBINE.

No. 853,925.

Specification of Letters Patent.

Patented May 14, 1907.

Application filed February 26, 1906. Serial No. 302,973.

To all whom it may concern:

Be it known that I, HANS HOLZWARTH, a citizen of Germany, residing in Hamilton, Butler county, Ohio, (post-office address Hamilton, Ohio,) have invented certain new and useful Improvements in Gas-Turbines, of which the following is a specification.

This invention, pertaining to gas turbines, will be readily understood from the following description taken in connection with the accompanying drawings in which:

Figure 1 is a vertical longitudinal section illustrating a construction of gas turbine embodying my invention: Fig. 2 a vertical transverse section in the plane of line *a* of Fig. 1, viewed from the left: Fig. 3 a vertical transverse section in the plane of line *b* of Fig. 1, viewed from the right, the outer section of the turbine-casing being removed, 20 and a part of the turbine wheel being broken away: Fig. 4 a vertical transverse section in the plane of line *c* of Fig. 1, viewed from the left: Fig. 5 a vertical transverse section, on a smaller scale, in the plane of line *d* of Fig. 25 1, view from the left: and Fig. 6 a horizontal section, on an enlarged scale, in the plane of line *e* of Fig. 1, through one of the nozzles, the turbine appearing in plan.

In the drawings:—1, indicates a bed-plate: 30 2, a shaft bearing: 3, the turbine shaft: 4, the turbine thereon: 5, the coupling-part on the shaft, to adapt the general machine to connection with machines to be driven: 6, the turbine casing: 7, a circumferential series of explosion chambers formed at one wall of the casing: 8, a circumferential series of nozzles, one for each explosion chamber, these nozzles leading from the explosion chambers to position to direct the gases to the vanes of the turbine: 9, valves normally closing communication between the explosion chambers and the nozzles, these valves opening from the explosion chambers and toward the turbine, there being one for each explosion chamber: 10, a 40 spring of adjustable tension connected with each of the valves and tending to hold it to its seat: 11, a large hollow bearing in axial alignment with the turbine shaft: 12, an annular air-chamber in the bore of this bearing: 13, an air inlet connection to this air chamber, the same being adapted for connection with any suitable source of air supply under pressure: 14, an annular gas chamber formed within the bore of the bearing 11: 15,

a gas inlet communicating with this gas chamber and adapted for communication with any suitable source of supply of gas under pressure: 16, exhaust outlet from the turbine-casing: 17, a hollow revolver, considered as a whole, turning within the bearing 11: 18, a bearing formed within the circle of the explosion chambers, its axis being coincident with that of the turbine and revolver: 19, the hollow head of the revolver turning within the bearing 18: 20, a diametrical partition in the revolver, dividing its general interior into two portions, one devoted to air and the other to gas: 21, a passageway leading from one of the general chambers of the revolver into constant communication with the air chamber 12 in the revolver bearing: 22, the air chamber in the head of the revolver: 23, a portion of the cavity of the general revolver forming a passage placing air passage 21 in constant communication with air chamber 70 22: 24, a passage placing the second general chamber of the revolver in constant communication with the gas chamber 14 of the bearing: 25, the gas chamber in the head of the revolver: 26, a portion of the general cavity 75 of the revolver, placing gas passage 24 always in communication with gas chamber 25 in the head of the revolver: 27, a port leading from each explosion chamber into the bearing 18, these ports being normally closed 80 by the general periphery of the head of the revolver: 28, a port leading outwardly from the air chamber 22 in the head of the revolver and adapted, as the revolver turns, to communicate with the explosion chambers in 85 succession through their ports 27: 29, a similar port leading outwardly from gas chamber 25 and adapted, as the revolver turns, to place the gas chamber in communication with the explosion chambers successively: 90 30, a worm wheel fast on the revolver: 31, a worm engaging the worm wheel: 32, a motor connected with the worm to serve in giving it rotation at selective speed: 33, an igniter carried by the periphery of the head of the 95 revolver and adapted, as the revolver turns, to present itself to the ports 27 of the explosion chambers in succession: 34, collecting rings mounted on the revolver but insulated from it: 35, conductors connecting the collecting rings with the igniter: and 36, electrical connections for bringing current to the 100 collecting rings and vitalizing the igniter.

2

Springs 10 holding the valves at the explosion chambers closed are to be adjusted to desired pressure of exit of gases from the explosion chambers. Air is to be supplied constantly to connection 13 at the proper pressure, thus constantly maintaining a pressure of air in air chamber 22 of the revolver head. Gas of proper pressure is to be supplied constantly to connection 15, thus constantly maintaining a pressure of gas in the gas chamber 25 of the revolver head. Current is to be brought to the collecting rings to vitalize the igniter. The revolver is constantly turned by the motor at appropriate speed. As the revolver rotates, the air port 28 delivers a charge of compressed air to the combustion chambers in succession. Following this, the port 29 delivers a charge of compressed gas into each of the chambers in succession. Following this the igniter explodes the mixture in each explosion chamber in succession. As a result of the explosion the valves of the explosion chambers are forced open and the products of the explosions pass through the nozzles and go to the turbine.

The gas pressure should always be somewhat greater than the air pressure. Oil may be utilized as a fluid in the machine. The number of wheels constituting the rotor of the turbine, as well as the number of pairs of chambers in the revolver, and the number of explosion chambers, may obviously be varied, and the character of the igniter is immaterial so long as it is adapted for its work. The particular construction set forth in the drawing is to be viewed as exemplifying and schematic.

I claim:—

1. In a gas turbine, the combination, substantially as set forth, of a turbine-rotor, a casing therefor, an explosion chamber having an inlet and an outlet, a valve at said outlet opening away from the explosion chamber, a spring holding said valve normally closed, a nozzle leading from said outlet to the vanes of the turbine-rotor, a revolver having an air-chamber and a gas-chamber provided each with an inlet connection and with an outlet port adapted to place them in successive communication with the inlet to the explosion chamber, an igniter carried by the revolver across the inlet to the explosion chamber, and means for rotating the revolver.

2. In a gas turbine, the combination, substantially as set forth, of a turbine-rotor, a casing therefor, a series of explosion chambers each having an inlet and an outlet, a valve at each of said outlets opening away from the explosion chambers, a spring holding each valve normally closed, a nozzle leading from each outlet to the vanes of the turbine-rotor, a revolver having an air-chamber and a gas-chamber provided each with an inlet connection and with an outlet port adapted to place them in successive communication with the inlets to the explosion chambers, an igniter carried by the revolver across the inlets to the explosion chambers, and means for rotating the revolver.
